UNITED STATES PATENT OFFICE.

GUSTAV FLÜGEL, OF BERLIN, GERMANY, ASSIGNOR TO GENERAL ELECTRIC COMPANY,
A CORPORATION OF NEW YORK.

CENTRIFUGAL COMPRESSOR.

1,326,043.

Specification of Letters Patent. Patented Dec. 23, 1919.

Application filed March 15, 1917. Serial No. 155,099.

To all whom it may concern:

Be it known that I, GUSTAV FLÜGEL, a subject of the German Emperor, residing at Berlin, Germany, have invented certain new 5 and useful Improvements in Centrifugal Compressors, of which the following is a specification.

The present invention relates to centrifugal compressors and has for its object to 10 provide an improved structure in compressors whereby pulsation will to a greater extent than heretofore be prevented.

For a consideration of what I believe to be novel and my invention, attention is directed to the accompanying specification and the claim appended thereto.

In the accompanying drawings, Figure 1 is a diagram as will be explained herein-after; Fig. 2 is a diagrammatic section of 20 an impeller; Fig. 3 is a diagrammatic side elevation of a portion of the impeller shown in Fig. 2, Fig. 4 is a diagram similar to Fig. 3 illustrating a modification, and Fig. 5 is a diagram of another modification.

25 It is already known that in centrifugal compressors the so-called pulsation area P, see Fig. 1, within which the machine is not usable on account of the occurrence of pulsations always comes before the peak S of the characteristic curve, by "characteristic" being understood the well known graphic representation of the relation between the pressure H on the delivery side of the machine or on the delivery side of an impeller 30 and the suction volume, the ordinates of the curve being plotted in terms of discharge pressure and the abscissæ of the curve being plotted in terms of volume. With a pure falling characteristic, therefore, a centrifugal compressor will not pulsate at all. By a pure falling characteristic is meant a characteristic curve according to which the pressure gradually drops as the volume increases. With multi-stage compressors the pulsation 35 point P is moved beyond the peak S to the falling branch of the characteristic curve; but it has also been found that a compressor will not pulsate if each individual stage thereof is so equipped with wheels that, when 40 tested individually, it has a purely falling characteristic, with constant density of the air sucked in. Thus, in order to reduce pulsations as much as possible, or to obviate them entirely, it is necessary to bring the 45 peak S of the characteristic curves of the dif-

ferent stages as near as possible to the starting point A, or, in other words, to attempt to obtain purely falling characteristics entirely.

I have discovered that this result may be 60 reached if the angle of exit from the running wheel, or the diameter of the running wheel, is made variable. This result may be attained by a construction like that shown in Figs. 2 and 3, in which 10 represents the 65 center line of the shaft 11 of an impeller wheel; 12 the blades; 13 the admission opening to the wheel, and 14 the wheel disks between which the blades 12 are located. While the ends of the blades of the running 70 wheel are located in a circle having a diameter d^2 , the wheel disks 14 extend to a diameter D^2 . The result is that with a full amount of flow a pressure is established corresponding to a running wheel having the 75 diameter d^2 ; with zero flow on the contrary the entire mass of air within the running wheel will in consequence of the friction of the walls be forced to rotate and thus a comparatively greater pressure will be estab- 80 lished equivalent to that which ordinarily would be obtained by a running wheel of the larger diameter D^2 . With increasing quantity of flow the influence of the friction of the walls will decrease according to the in- 85 creasing radial component of the velocity of flow. In this way, therefore, it is possible to force forward the points of the characteristic curve artificially in proportion as they are situated nearer to the axis of ordinates 90 OA, and thereby to produce even purely falling characteristics.

The above object is obtained in a still more complete manner by a construction according to Fig. 4. While the ends of the buckets 95 have the same distance from the axis as the rims of the disk, the buckets instead of running forward constantly outside the circle of the diameter d^2 are bent sharply backward as indicated at 15, this being done by 100 reason of the fact that with a full amount of flow they are no longer capable of accelerating the air which is flowing from the compressor. Consequently, in this construction also, in case of a full supply, a delivery 105 pressure will be established which corresponds to a running wheel of diameter d^2 ; with zero flow, a delivery pressure corresponding to a running wheel of the diameter D^2 will be established; and with a par- 110

tial supply, a delivery pressure corresponding to wheel diameter intermediate between d^2 and D^2 will be established. By this means it is perfectly possible to produce purely 5 falling characteristic curves.

It will also be understood that the two arrangements; viz. that shown in Figs. 2 and 3, and that shown in Fig. 4, may be combined into a single structure, in which case 10 the vanes would not only terminate short of the disks of the running wheel, as shown in Figs. 2 and 3, but at their ends would be curved as shown in Fig. 4. Such an arrangement is shown in Fig. 5 in which 18 15 indicates the vanes curved or bent sharply backward at their radially outer ends as indicated at 19 and 20 and the periphery of the disks of the running wheels. As will be clear from the figure the vanes 18 terminate 20 short of the periphery of the disks 20.

In accordance with the provisions of the patent statutes, I have described the principle of operation of my invention, together with the apparatus which I now consider to

represent the best embodiment thereof; but 25 I desire to have it understood that the apparatus shown is only illustrative, and that the invention can be carried out by other means.

What I claim as new and desire to secure 30 by Letters Patent of the United States, is,—

In a centrifugal compressor for handling gases, which compressor is subject to pulsations at light load, an impeller wheel having blades and side disks, the ends of the blades 35 being a less distance from the axis than the peripheries of the disks and adjacent their outer ends being bent backward away from their normal direction whereby the impeller wheel is given a substantially purely falling 40 characteristic.

In witness whereof, I have hereunto set my hand this 23rd day of December, 1916.

GUSTAV FLÜGEL.
